PRINTING MACHINE

Blackwell K. Murchison, Brooklyn, N. Y., assignor
to Mastalign Corporation, New York, N. Y., a
corporation of New York

Application February 3, 1939, Serial No. 254,372

21 Claims. (Cl. 101—95)

The invention relates to printing machines, and more particularly to a machine in which a single line of printing characters is set and an impression is made therefrom prior to the setting of, and the making of an impression from, a succeeding line of printing characters, wherein means are provided to ensure accuracy and rapidity in the setting of succeeding letters in a line and in justifying each line prior to the making of an impression therefrom.

The present invention is an improvement in the printing machine shown in Letters Patent No. 2,145,271 granted to me under date of January 31, 1939. This machine comprises a plurality of type carrying members mounted upon a single rotary shaft, means being provided to rotate the shaft and the members to bring the desired types into the printing position, to lock each member after the proper type has been set, 20 and to disengage the shaft from each member after it has been set preparatory to the actuation of the succeeding type carrying members in setting up a line of type. This operation is repeated until the types for a line of the desired 25 length have been set.

Following the setting up of each word, a justifying mechanism carried by each of the type carrying members is set, and after a complete line has been set, these various mechanisms are 30 actuated to separate the discs to form spaces between words. The construction of the various parts is such that these spaces will all be equal but all will vary in width according to the number of letters and the number of words in a line.

With types arranged circumferentially about discs actuated by a shaft, the shaft must be turned to a variable extent to bring different types into the printing position, and since each disc carries a full font of type including upper and lower case letters, numbers, punctuation 40 marks and other characters, the operator must proceed with extreme care in setting up each type in order to have the proper printing character brought to the printing position for making the impression, and must ascertain the exact 45 number of words in each line in order to determine whether there will be adequate spacing of the words prior to the making of each impression.

Furthermore, in a machine of the type above referred to, an operator is required to actuate the type setting bar after each type has been brought to the printing position, to disengage it from the type carrying member which has just 55 been set, and to engage the locking bar there-

with. The actuation of the main shaft and the various discs is by hand, which tends to slow down the operation of the machine.

Upon the conclusion of the setting of the types of each word, the justifying mechanism carried by the member having the last letter of a word is so actuated as to bring it to a position permitting the separation of the type carrying members to form the spaces between the words after a complete line has been set. The mechanism for disengaging the setting bar and for engaging the locking bar with each type carrying member as it is set, has two succeeding operations, the main shaft between these operations being actuated when the justifying mechanism is to be set. This mode of operation required the use of one hand of the operator for actuating the setting and the locking bars, and required considerable acquired skill to develop a reasonable speed in the actuation of the machine.

Furthermore, in said machine the printing characters are arranged around the periphery of a hand wheel used in turning the main shaft, and the operator is required to closely watch this hand wheel, as well as the copy being followed, to bring the proper letter or other printing character into the printing position. With printing characters positioned entirely about the periphery of the hand wheel, an unskilled operator may 30 turn the wheel throughout approximately 360° in searching for the right printing character, or impart greater movement to the wheel than is necessary. Either of these conditions may result from turning the wheel in the wrong direction. The operator may also turn the wheel in the wrong direction, thus requiring greater movement of the wheel than is actually necessary to bring the desired letter into the printing position. This condition also tends to slow 40 down the operation of the machine, as does the necessity for referring to the proof sheet in order to determine the number of spaces required in a line of type which has been set.

With the above conditions in mind, I have provided in a machine of the type above referred to, a visual indicator mechanism independent of, but actuated from the hand wheel for actuating the main shaft, which mechanism will not only show what printing character is in the printing 50 position, but the quantity and direction of movement necessary to bring the succeeding character into that position with the least movement of the shaft. By providing a copy holder adjacent this indicator mechanism, the operator may 55

readily follow both the indicator mechanism and the copy and impart to the hand wheel the shortest movement necessary to bring the succeeding letter into the printing position.

5 I also provide in the machine a second indicator mechanism selectively actuated through the wheel for turning the main shaft, showing the number and location of the justifying mechanisms which have been set during the setting 10 of each line of type, so that when a complete line of type has been set up, the operator may at a glance determine whether the line will be properly justified by the actuation of the justifying mechanism or whether there are too many 15 letters in a line to permit the line to be completely filled out with adequate spacing between words. This spacer indicator shows at all times the members which have been set and hence may also be used by the operator to guide him in 20 dividing words at the end of the line or using the type carrying members as quads for spacing purposes.

This mechanism is so constructed that it will be automatically actuated simultaneously with 25 the turning of the shaft for setting the justifying mechanism of any type carrying member to indicate that the justifying mechanism of the member which has just been set has been actuated, but in addition to this will be actuated 30 with each full actuation of the setting bar to indicate the last disc which has been set. Means are also provided to restore the spacing indicator to a normal or neutral position following the setting and justifying of each line of type or 35 the making of an impression therefrom.

In addition to the indicators above referred to, I provide an electrically actuated mechanism for imparting the desired movement to the setting bar and the locking bar, as well as to the justifying 40 mechanism indicator.

In a machine embodying the invention, the set type indicator is actuated by and in accordance with movements of the main shaft, while the spacing indicator, while actuated with each 45 actuation of the setting bar, is normally inoperative to indicate the setting of the justifying mechanism of a type carrying member, but may be manually connected with the main shaft through the hand wheel, so that the actuating means of this indicator may be selectively actuated by a coupling mechanism adapted to be 50 connected with the hand wheel by one hand of the operator.

The mechanism for actuating the setting and 55 the locking bars, and the actuating means for the spacing indicator is conveniently located adjacent the hand wheel, so that the mechanism may be tripped or set in motion within a wide range in the positioning of the hand in turning the wheel.

60 It has been found necessary to provide an actuating mechanism for the setting and the locking bars which will operate substantially instantaneously, so as to avoid all those delays incidental to the disengagement of the hand with the setting wheel carried by the main shaft in order to actuate the said setting and said locking bars.

To accomplish this result, I provide electrical 70 control members, and to adapt the machine to universal use, this mechanism is so constructed as to be adapted to either alternating or direct current.

In a machine embodying the invention, the 75 operator may use both hands in connection with

hand wheels carried by the main shaft at opposite ends of the bank of type carrying members, and may actuate the setting and the locking bars and the spacing indicator without removing one hand from the main setting wheel, although 5 movement of the hand along the wheel may be necessary when connecting the actuating means for the spacing indicator with the hand wheel.

The invention consists in the novel features of construction and combination of parts herein-after set forth and described, and more particularly pointed out in the claims hereto appended.

Referring to the drawings,

Fig. 1 is a plan view laterally condensed of a machine embodying the invention;

Fig. 2 is a detail end view showing the manner of actuating the set type indicator;

Fig. 3 is an enlarged plan view of the indicator of the justifying mechanism;

Figs. 4 and 5 are enlarged fragmentary sectional views on the lines 4-4 and 5-5 of Fig. 3;

Fig. 6 is a fragmentary view of the electrical actuating means for the setting and the locking bars and the justifying indicator mechanism;

Fig. 7 is an enlarged sectional view on the line 25 1-1 of Fig. 6;

Fig. 8 is a detail sectional view of the clutch for actuating said mechanism on the line 8-8 of Fig. 7; and

Fig. 9 is a wiring diagram showing the electrical conditions in said mechanism.

Like numerals refer to like parts throughout the several views.

In the drawings, the frame of the machine is indicated at 10, the main shaft at 11 and the various type carrying members or discs at 12.

The shaft 11 is provided with keyways 13, in one of which the setting bar 14 is slidably mounted. The shaft 11 is turned by means of a hand wheel 15 having thereon printing characters 16 and having a sequence of edge notches 17, one for each printing character about the periphery of the hand wheel.

The various discs are provided with notches about the periphery thereof adapted to be engaged by a locking bar 18.

The setting bar 14 and the locking bar 18 are actuated by means of a sleeve 19 idly mounted upon the shaft 11 so as to be adapted to be advanced along the shaft 11 with a step by step movement by the mechanisms, shown and described in my aforesaid Letters Patent. The manner of connecting the setting bar 14 with said sleeve is as shown and described in said patent. The said sleeve has movement imparted thereto along the shaft 11 by a rack 20 actuated from a shaft 21 having a crank arm and handle 22. The means for imparting reverse movement to the sleeve 19 after an impression has been made from a line of type and before the printing characters have been distributed, consists of a pull cord 23 and means actuated by a crank arm 24, also as shown and described in said Letters Patent.

The impression platen is shown at 25 and the paper feed cylinder associated therewith at 26. The movable header engaging one end of the bank of type carrying members is shown at 27, the fixed header at 28 and the rods forming a part of the stop mechanism for said movable header at 29. The rack bar for moving the header 27 is shown at 30.

The detailed construction of these various parts and their mode of operation is as described in my aforesaid patent. The detailed construc- 75

tion of these mechanisms is immaterial to the present invention, and reference is had thereto and not to other parts of the machine of said patent, since an understanding of the present invention is possible without referring to such other details.

The operation of the various mechanisms of the machine of the present application, except as to the mechanisms which are about to be described, is the same as in my aforesaid Letters Patent.

All of the mechanisms forming a part of the present invention have to do with the operation of the machine in setting a line of type and in justifying each line after it has been set.

In setting up a line of type, the various type carrying members 12 are turned by the shaft 11 until the desired printing character is in the printing position. The setting bar 14 is then disengaged from the member at the left of those engaged by it, and the locking bar engaged with that member. All discs, except the one at the left above referred to, remain connected with the shaft 11 so as to be rotatable therewith. Both the setting bar and the locking bar receive two impulses during the procedure of actuating each disc to set a type in the line to be printed. When the spacing of words is required, the mechanism used for justifying a line of type is set, the actual spacing of words occurring as a result of movement of the shaft 11 after a full line of type has been set. The setting of the justifying mechanism occurs between the two impulses incidental to the setting of the type carrying member, this mechanism being carried by the member carrying the last letter of a word.

The turning of the shaft 11, which may be in either direction, is a hand operation. There may be sixty or more of the type carrying members 12 in a bank which, together with the shaft 11, possess considerable weight. When the left hand alone is used in turning the shaft, the operation of the machine of said Letters Patent, to secure the desired nice locating of the character to be printed, is slow and somewhat difficult, particularly when, during the setting operation, a considerable turning movement of the shaft is required, at which time the right hand of the operator is idle.

To increase the ease of operation of the machine in setting a line of type, I provide a second hand wheel 31 carried by the header 27, so that the right hand may be mainly relied upon in turning the shaft, but both hands may be so used and may be kept in engagement with the two wheels 15 and 31 at all times while a line of type is being set. In this manner the speed of operation of the machine may be greatly increased.

In the event of a typographical error in setting a line of type, it is necessary to re-set the whole line, or that part of the line including the error. Hence, extreme care is required in operating the machine to prevent the making of an impression of any line in which a typographical error occurs, since this would result in the necessity for re-setting all the printed matter appearing upon the sheet at the time.

To permit an increased speed of operation in the machine and at the same time lessen the possibility of an improper actuation of any type carrying member, I provide what is herein termed "a set indicator" actuated by and in accordance with the movement of the hand wheel 15. This indicator shows the movement of the type carrying member being set and what letter upon that

type carrying member has been brought to the printing position.

As will more fully appear hereinafter, this mechanism also enables the operator to determine in which direction the shaft 11 can be turned with the least quantity of movement required to bring a desired character into the printing position.

The set indicator comprises two gauge plates 32 and 33 having indicated thereon, printing characters corresponding with, and in the same spaced relation to each other as, the same printing characters carried by the members 12.

These gauge plates are spaced one from each other a distance to afford clearance for a traveling tape 34 having indicia thereon adapted to register with the various characters upon one or the other plate 32 or 33. The characters upon the plate 32 correspond with those throughout 180° of each member 12, and those upon the plate 33 correspond with the characters about the remaining 180° of said members.

The indicia upon the tape 34, consisting of an arrow 35 pointing toward the plate 32, indicates what character upon this plate is in the printing position, while the indicia consisting of an arrow 36 pointing toward the plate 33, indicates what character upon this plate is in the printing position. These arrows are arranged upon the tape a distance apart equalling 180° of the circumference of the various printing members.

The tape 34 is of substantially non-stretchable material such as steel.

Upon one of the plates as 32 is an arrow or other indicia 37 indicating a point of the periphery of the various members 12 at which no printing character occurs, so that the operator, prior to the making of an impression, can turn the shaft 11 in a manner to bring all members 12 which have not been used in setting the line of type, to a neutral position or one where no character is positioned in the printing line. This also permits the use of any of the printing members as a quad.

The tape 34 has a length substantially three times the circumference of the hand wheel 15, and in its run passes about various guide sheaves 38 defining the course of travel of the tape and also about the hand wheel 15 from which it is driven.

One of the guide sheaves 38, adjacent the far end of the plates 32 and 33, is mounted in an adjustable bearing bracket 39 acted upon by an adjusting screw 40 by means of which any slack in the tape may be taken up to permit the accurate setting of the indicia 35 and 36 in relation to the printing characters upon the plates 32 and 33. There are three arrows 35 and three arrows 36 along the length of the tape spaced apart, as heretofore stated, a distance equalling 180° of the circumference of the wheel 15.

The plates 32 and 33 are located at the top of the machine within a clear field of vision of the operator and may have associated therewith a rack 41 for holding copy closely adjacent the plates. This permits the operator to follow the copy and follow the movement of the various type carrying members without giving any attention to any other of the mechanisms of the machine.

The location of the indicia 35 and 36 in relation to the characters upon the plates 32 and 33, and to a center line 42 upon each said plate, indicates to the operator the shortest amount and direction of movement of the shaft 11 necessary

to bring a desired character into the printing line.

While the set indicator discloses what letter is brought into the printing position with each actuation of the machine in setting a line of type, it does not indicate how many letters have already been set in that line nor how many words are contained in the line. To meet this condition, I provide in the machine a justifying indicator mechanism which will register the number of letters which have been set up and the number of justifying mechanisms which have been set, and hence the number of letters and the number of spaces appearing in the line. This mechanism, like the set indicator, is actuated from the hand wheel 15.

The justifying indicator mechanism is within a clear line of vision of the operator, being positioned adjacent one end of the bank of type carrying members. This enables the same mechanism which actuates the setting bar and the locking bar to be used to operate said indicator mechanism.

No attention need be given the justifying indicator mechanism while an operator is setting a line of type. When the set-up of the line is almost completed, the operator may consult this indicator mechanism and see how many letters have been set and how many spaces will appear in the line, so as to permit accuracy in the setting of the final letters of the line and to permit the use of a quad or a justifying mechanism, or both, in bringing the last letter to the extreme end of the line.

In the embodiment of the invention shown in the accompanying drawings, this justifying indicator comprises a base 43 having a plurality of transverse grooves therein corresponding in number with the number of type carrying members 12. These grooves are spaced apart a distance equalling substantially one-half the thickness of the type carrying member, leaving an exposed space between the grooves of the same width as the grooves themselves.

Slidably mounted in each groove is a gauge slide 44 having one end thereof of a length to project beyond the base 43 toward the sleeve 19 and shaft 11. This projecting end, as shown in Fig. 4, is positioned below the base.

The base 43 is provided with a longitudinal rib 45 having indicated thereon consecutive numbers, there being one number adjacent each gauge slide 44.

Pivotedly mounted upon the sleeve 19, so as to be movable with the setting bar 14, is an index finger 46 normally held by a spring 47 in engagement with the top of the base 43 in close abutting relation to the rib 45. The index finger 46 has movement with the sleeve 19 along the shaft 11, and at the same time is capable of movement toward and from the base 43.

Upon the under face of the index finger 46 is a cam 48 adapted to impart longitudinal movement to any gauge slide upon lifting of the index finger, although normally so formed as to permit movement of the index finger along the base plate without contacting with any gauge slide.

A stop screw 49 may be used to limit the oscillatory movement of the index finger by the spring 70 47.

Pivotedly mounted upon the under side of the base 43 is a frame 50, the bar 51 of which extends longitudinally of the base throughout substantially its full length, being positioned below 75 and in operative relation to the index finger 46,

along which this finger moves with movement of the sleeve 19. This frame is provided with a projecting end 52 by means of which the frame may be rocked with movement of the hand wheel 15. The bar 51 is of a length to engage the index 5 finger at any point of its movement along the base plate by said sleeve 19.

In the operation of the justifying indicator slides, means are provided adjacent the hand wheel 15 for imparting rocking movement to the frame 50 whenever it becomes necessary in the operation of the machine to set a justifying mechanism carried by any disc.

This means, in the form of the invention shown, comprises a slide 53 mounted in a suitable slide-way in a bracket 54 carried by the frame of the machine. This slide is acted upon by a retracting spring 55 extending from adjacent the lower end of said slide to the said bracket. One end of this slide is provided with a tappet 56 extending over and adapted to engage the projecting end 52 of the frame 50 when the slide is connected with and receives movement from the hand wheel 15.

Carried by the bracket 54 and passing through 25 a slot 57 in the slide 53 is a spring stud 58 engaging said slide and having a normal tendency to hold it in engagement with the bracket 54, and to hold a lock tongue 59 carried by the slide out of engagement with the edge notches 17 of 30 the hand wheel 15.

As will more fully appear hereinafter, the justifying indicator mechanism is used during the setting of each line of type, and is restored to its normal, fully inoperative condition, following the 35 setting of the line. As the justifying mechanism of any type carrying member is set, the movement of parts necessary to set this mechanism will impart movement to the index finger 46 in a manner to cause the cam 48 thereon to force 40 a gauge slide 44 out of alinement with the other gauge slides and thus indicate that on certain discs the justifying mechanism has been set.

Upon the base 43 opposite to the edge thereof along which the index finger 46 travels, is a restoring bar 60 mounted for right line movement upon links 61 and 62. Acting upon said restoring bar is a spring 63 normally holding it outwardly of said base 43 and out of engagement with any of the gauge slides 44.

The link 61 is provided with an actuating arm 64 adapted to be engaged by a pin 65 carried by the sleeve 19 when said sleeve has received its maximum movement along the shaft 11, this arm 64 having a thumb piece 66 permitting manual 55 movement of the restoring bar.

It will be observed that the actuation of a gauge slide and the actuation of the set indicator tape 34 is, in each instance, by the hand wheel 15. The set indicator does not in any way inform the operator of the number of letters which have been set, or the number of spaces which have been provided for by the setting of justifying mechanisms of different discs. The justifying indicator is actuated each time that the tape 65 34 receives movement, and thus registers the number of letters which have been set and the number of type carrying members upon which the justifying mechanisms have been set. Hence, by combining in the same machine these two 70 mechanisms operated simultaneously and from the same source, the exact working conditions in and about the machine in setting a line of type are indicated to the operator at all times.

The tongue 59 of the slide 53 may be selectively 75

engaged with any notch 17 of the hand wheel 15, and thereafter with the turning of this wheel away from the operator, the frame 50 is rocked in a manner to actuate the index finger 46 and its cam 48 in a manner to impart movement to the gauge slide 44 opposite which it may be at the moment. This mode of operation will be more fully described later.

To permit increased speed in the operation of 10 a machine, it is desirable to provide motor actuated means, the control mechanism of which is conveniently accessible to the left hand of the operator, grasping the hand wheel 15, for actuating the sleeve 19, and with it the setting and 15 locking bars operatively connected therewith.

This control mechanism and the source of power, the application of which to the machine is determined by the actuation thereof, will now be described.

20 The power for actuating the setting and the locking bars and the justifying indicator is derived from a motor 67 through a speed reducing mechanism 68, both of well known construction. The power of said motor and said mechanism is 25 applied to a driving shaft 69 carrying a flywheel 70. Said motor, while the machine is in use, is in continuous operation.

Associated with said driving shaft 69 is a driven shaft 71 adapted to be connected therewith by a 30 clutch mechanism similar to that commonly used in an ordinary punch press.

Carried by the shaft 71 is a crank 72 connected by a link 73, having a spring 74 in the length thereof, with the crank of the handle 22.

35 The clutch mechanism above referred to includes therein a clutch pin or dog 75 having a slot 75a adapted to enter one of two clutch sockets 76 in the flywheel 70, said pin being acted upon by a spring 77 adapted to normally thrust 40 said clutch member outwardly of the driven shaft into engagement with a clutch socket 76. The action of the spring 77 is restrained by means of a pivotal arm 78 having a cam surface 79 thereon adapted to enter the slot 75a, said arm being 45 adapted to enter a channel 80 of a collar carried by the driven shaft. The arm 78 is normally positioned in a channel 80 in a housing 81 carrying the clutch so as to prevent movement of the pin or dog 75 toward the flywheel 70.

50 During the operation of the machine, the clutch mechanism for connecting the driving shaft 69 with the driven shaft 71 must be set twice with the setting of each type carrying member 12 without regular intervals between the actuation 55 of the clutch, and the actuating means for the clutch must be of a nature limiting the operative moment of the crank 72 to one full revolution without possibility of failure of the release of the clutch, irrespective of continued actuation of the 60 control mechanism for causing setting of the clutch. While the speed of the driving shaft is not critical, in the form of the invention shown it turns at the rate of approximately one hundred revolutions per minute. Consequently the clutch 65 must be set and also released within a fractional part of a second, and no timing factor as to the actuation of the manually operative control mechanism is required to accomplish this result.

The actuating means for the arm 78 consists 70 of a solenoid 82, the core 83 of which is connected with the arm 78 by a link 84. The circuit to the solenoid 82 is controlled by an electrical relay system, such as that shown in Fig. 9 of the drawings, and by a manually operative switch mechanism consisting of a fixed contact member 85

mounted adjacent the wheel 15, and a movable contact member 86 carried by an arm 87 having a segmental end 88 overlaying and extending throughout the upper portion of said wheel, so as to be readily accessible to the operator of the 5 machine with different positions of the wheel within the normal range of movement when setting different discs. The length of the arcuate portion 88 may be approximately 90° of the circumference of said wheel. 10

The contacts 85 and 86 are normally separated by means of a spring 89 sufficiently light to make the switch mechanism extremely sensitive to the touch of the operator.

Leading from the source for actuating the solenoid 82 are wires 90 and 91 controlled by a main switch mechanism 92. This source may either be of alternating current or direct current. 15

A wire 93 leads from one side of the source to one of the contacts 85 of the switch mechanism 20 85-86, and a wire 94 leads from the other contact of said switch to a winding 95 of the solenoid of a relay mechanism. Leading from the solenoid 95 is a wire 96 to the other side of the line 90-91. 25

The solenoid 95 actuates two contacts 97 and 98, connected in parallel, simultaneously with the energizing of said solenoid, to close a circuit through wires 99 and 100, contact 101 and wire 102 to the winding of the solenoid 82.

Arranged in this line is a resistance element 30 103 for use when using a direct current source, and in shunt with this resistance is a switch mechanism 104 for use when using an alternating current source.

The switch mechanism 97 is normally open. 35 The switch mechanism 101 is normally closed.

Actuated by the core of the solenoid 82 is a switch mechanism 105, the contacts of which are arranged in a line 106, one branch of which leads to the winding 107 of a solenoid of a circuit interrupter switch mechanism including the contact 101 and a holding circuit including a second contact 108 actuated by the solenoid 107 and connected by a line 109 with the contact member 98. The circuit to the solenoid 107 is closed through a wire 110 connected with the wire 106 45 and a wire 111 connected with the wire 96.

Connected across the switch 101 from the wire 100 to the wire 102 is a spark suppressor consisting of a condenser 112. 50

The operation of the herein described printing machine is substantially as follows:

The operator of the machine, when bringing a printing character into the printing position, uses both hands in turning the shaft 11, one upon the wheel 15 and the other upon the wheel 31. All type carrying members 12 which have not been brought with a character into the printing position are turned with the shaft. 55

As the shaft is turned, lineal traverse is imparted to the tape 34 in relation to the plates 32 and 33 until the arrow 35 or 36 indicates what letter or character is in the printing position upon the disc being set and all other discs having movement with the shaft. 60

When beginning to set up a line of type, the arrow 35 will be in register with the arrow 37, indicating that none of the discs is so positioned as to have any printing character in the printing position, or, as when an impression is to be made, 70 those discs which have not been used in setting a line of type, have no character in the printing position.

The position of the arrow 35 or 36 in relation to the center line 42 apprizes the operator of the 75

least quantity of turning movement of the shaft 11 which will suffice to bring a required character into the printing line.

Each plate 32 and 33 is of a length to correspond with 180° of turning movement of the shaft.

With the conditions as shown in Fig. 1, if the next letter to be set is "o", or the third letter beyond the blank space upon each disc indicated by the arrow 37, the operator knows that the shaft may be turned only a distance corresponding with the space of three letters upon the disc, and that the disc must have contra-clockwise movement from the left of the machine. If the letter required should be "u", then the operator knows that a clockwise movement, corresponding in length with the space occupied by four letters, must be imparted to the shaft.

Since the arrows 35 and 36 are spaced apart a distance equalling 180° in arc of the disc, it is obvious that the first letter upon the plate 32 and the first letter upon the plate 33 will be positioned upon the disc diametrically opposite each other.

With the use of the tape 34, the operator may rapidly turn the shaft either clockwise or contra-clockwise, and the arrows upon the tape, with its movement by the hand wheel 15, permit the operator to follow the movement of the wheel 30 and of the discs by watching the tape, so that no difficulty may be experienced in accurately turning the shaft and stopping its movement in setting each letter. The tape also permits accuracy in the stoppage of the shaft 11 so as to ensure a proper positioning of the various mechanisms in the machine to lock each disc in the set position.

While the proofing mechanism described in my aforesaid Letters Patent may be used, if desired, the tape 34 acts as a proofing mechanism as to each letter as it is set.

While with the use of a steel tape there is little likelihood of stretch of the tape, I provide the adjusting mechanism 39-40, acting upon one of the guide rollers 38, to permit correction of any slight loss of adjustment in the tape due to stretch or slight inaccuracy in the length of the tape itself.

By providing a proof holder immediately above the plates 32 and 33, an operator may conveniently follow the copy and the tape 34 at the same time, and, in operating the machine, is required merely to use the eyes in following the copy and the tape.

After each letter has been set, it is necessary to actuate the setting bar 14 and the locking bar 18 by imparting movement to the sleeve 19 axially of the shaft 11. The mechanism used for imparting movement to the sleeve 19 through the shaft 21 and its crank arm 22 is as shown in my aforesaid Letters Patent. The herein described machine accomplishes this result by means of power instead of by hand, registers the number of movements of the sleeve during the setting of a line of type, and incidentally registers the number of justifying mechanisms which have been set during that period.

After a letter has been set, the operator merely touches the overhang 88 of the lever 87 carrying the movable switch member 86, thus engaging the contacts 85 and 86 and closing the circuit through the controlling relay mechanism to the solenoid 82.

With the energizing of the winding of this solenoid, movement of its core will raise the arm 78

and thus permit the spring 71 to engage the clutch pin or dog 75 with a socket 76 in the flywheel 70. Since the motor 67 is in continuous operation, this will impart one full revolution to the driven shaft 71 and the crank 72, thus rocking the crank arm 22 and imparting movement to the sleeve 19 equal to one-half the thickness of a disc 12.

With movement of this sleeve, the index finger 46 will move along the base 43 from a position on one side of a gauge slide 44 into alignment with that slide. The cam 48, by this movement, will be positioned below the slide and the finger 46 above the slide.

The construction of the control relay mechanism is such that irrespective of the length of time during which the contacts 85 and 86 are engaged, the clutch member 75 will be disengaged by the cam surface 79 from the flywheel of the driving shaft, upon the completion of one full revolution of said shaft. The action of the control relay mechanism securing this result will be more fully described hereinafter.

It is to be noted, however, that while the engagement of the contacts 85 and 86 is necessary to energize the solenoid 82, the de-energizing of this solenoid occurs irrespective of the continued engagement of said contacts. Hence, with each engagement of the contacts 85 and 86, the operation of the crank 22 and the mechanisms actuated thereby is limited to a single actuation.

The spring 74 in the length of the link 73 is merely for the purpose of providing a yieldable connection between the crank 22 and the crank 72 so as to avoid any extreme nicety in the construction and setting of these parts.

If, when a letter has been set, no spacing is required after the letter, the operator merely actuates the switch member 87 a second time, causing a repetition of the operation above described and a second movement of the setting and the locking bars to ensure further movement of the setting bar out of engagement with the justifying mechanism carried by the disc which has just been set. With this second movement of the sleeve 19, and two such movements are required with the setting of each disc, the index finger 46 again moves along the base 43, and the cam 48 carried by said finger moves out of engaging relation with the slide opposite which it was positioned with the first movement of the sleeve 19. The index finger 46 with this movement will indicate that the first disc has already been set and that the justifying mechanism of that disc has not been set.

These operations are repeated until a word has been completely set up, and the presence of a space between the last letter set and the next letter set is required.

When bringing the last printing character of a word into the printing line, the operation will be as heretofore described, up to the first actuation of the sleeve 19. After the operator has engaged the contacts 85 and 86, resulting in this first actuation of the sleeve 19, he engages the tongue 59 of the slide 53 with one of the notches 17 in the edge of the wheel 15 by pressing said slide toward the wheel 15 against the tension of the spring 55. When said tongue 59 is thus engaged with the wheel 15, said wheel is given a contra-clockwise movement, thus bringing the tappet 56 into engagement with the extension 52 of the frame 50 and rocking this frame in a manner to cause the bar 51 thereof, irrespective of the position of the index finger 46 in relation to the 75

base 43, to raise this finger. Since the first actuation of the sleeve 19 during the setting of each disc positions the cam 48 below and in operative relation to a slide 44, this movement of the index finger against the tension of its spring 47 will move the slide 44 transversely of the base 43 so as to project the far end thereof beyond the adjacent slides. This indicates that the justifying mechanism upon the disc which has just been set, has been set to cause the formation of a space when a line has been completely set and justification of that line is required.

The movable switch member 87-88 is then actuated to impart the second impulse to the setting and the locking bars.

The manner of mounting the frame 50 is such as to limit the movement of the wheel in a manner to always ensure one of the notches about the succeeding disc 12 being in the proper operative relation to the locking bar.

Immediately upon the stoppage of the wheel 15, the spring 58 acts to disengage the tongue 59 from the notch 17 with which it is engaged, thus permitting the spring 55 to impart a return movement to the slide 53 and move the tappet 56 out of engaging relation with the end 52 of the frame. To permit this mode of operation, the arrangement is such that the slide 53 has movement with the wheel 15 against the tension of said spring 55, and it is this movement of the slide with the wheel which causes the actuation of the frame 50.

After the second actuation of the sleeve 19 incidental to the setting of a letter and of the justifying mechanism of the disc carrying that letter, the wheel 15 is free to be turned in setting the desired letter upon the succeeding disc, since the spring 47, with the disengagement of the tappet 56 with the extension 52, causes downward movement of the index finger 46 as well as of the frame 50, so as to again position the cam 48 below the plane occupied by the various slides 44.

As the index finger 46 is advanced along the base 43 with a step by step movement in the manner above referred to, it will apprise the operator of the number of letters which have been brought into the printing line and the number of justifying mechanisms which have been set. When the setting of the type approaches the end of a line, the operator, by glancing at the index finger and the various slides 44 which have been displaced during the setting of the line, may estimate what space is available for further letters toward the end of the line. Hence, if necessary, the operator may actuate the movable contact 86 twice in rapid succession and thus set a quad in the line after turning the shaft so that the arrow 36 is opposite the arrow 37.

After a line has been completely set, whether it be a full line or a partial line, the various justifying mechanisms are actuated in the manner described in my aforesaid Letters Patent, an imprint is made, and the above operations are proceeded with in connection with the next line of type to be set.

After the impression has been made, the bar 60 has a parallel movement imparted thereto by the lever 64, this movement being against the tension of the spring 62. Said lever 64, connected with the link 61, may be manually actuated by means of the thumb piece 66 or may be automatically actuated by imparting continued movement to the sleeve 19 to a point where the pin 65 engages the thumb piece 66 and thus rocks the lever 64 through the power applied to the sleeve

19 with the same effect as when it is manually operated.

The spring 63 imparts a return movement to the restoring bar 60 when the arm 64 is released, thus re-setting the justifying register preparatory to the operation of the machine in setting the succeeding line of type.

While the machine is in operation, the driving shaft 69 and its flywheel 10 are continuously turned by the motor 67 through the speed reducing mechanism 68, and the driven shaft 71 is normally stationary except when the arm 78 is raised as a result of the energizing of the solenoid 82.

The operation of the control relay mechanism will now be described.

When the contacts 85 and 86 are engaged, a circuit is closed, this circuit including the wire 93, contacts 85 and 86, the wire 94, the solenoid winding 95 and wire 96, back to the source, thus closing the normally open contacts 97 and 98. When these contacts are closed as a result of the energizing of the solenoid 95, a circuit around the switch mechanism 85 and 86 is closed through the wire 99, switch 97, wire 100, switch 101 and wire 102 through the solenoid 82 and the wire 96 to the other side of the source.

When the solenoid 82 is energized, its core is moved upwardly, thus raising the arm 78 and at the same time closing the switch mechanism 105 to close a circuit including the wires 106 and 110, the solenoid 107 and the wire 111 to the wire 96, thus energizing said solenoid 107. The energizing of this solenoid opens the switch 101 and closes the switch 108. The opening of the switch 101 will immediately de-energize the solenoid 82 even though the contacts 85 and 86 continue in engagement. With the closing of the switch 108, a circuit including the wires 93 and 99, the contact 98, the wires 109 and 110, the solenoid winding 107 and the wires 111 and 96 is closed, thus continuing the energization of the winding of the solenoid 107 so long as the contacts 85 and 86 are engaged and the switches 97 and 98 are closed as a result of the continued energization of the solenoid 95. Consequently, it is immaterial how long the contacts 85 and 86 be engaged, since the circuit including the winding of the solenoid 82 will be interrupted instantly with the energizing of the solenoid 107 and this solenoid will remain energized until the contacts 85 and 86 are disengaged in a manner to de-energize the solenoid 95 and permit the interruption of the circuit to the solenoid 82 at the switch mechanism 97.

To summarize, the solenoid windings 95 and 82 will be energized with the closing of the contacts 85 and 86, and with the energizing of the solenoid 82, the solenoid 107 will be energized to interrupt the circuit to the solenoid winding 82. So long as the contacts 85 and 86 are engaged, the solenoids 95 and 107 will both be energized, but the solenoid 82 will continue deenergized. This results from the closing of the switch 98 by the solenoid 95 and the closing of the switch 108 by the solenoid 107. Hence, the solenoid 107 is energized from two sources, the contacts 105 controlled by the solenoid 82 and the switches 98 and 108, both of which are closed when the solenoids 95 and 107 are energized. When the solenoid 107 is energized, the circuit to the solenoid 82 is open at the switch 101, and this switch cannot be closed except by the de-energizing of the solenoid 95 as a result of the opening of the switch contacts 85 and 86.

The procedure followed in justifying the line of type is as follows:

type, making an impression therefrom and distributing the type after the impression is made, is the same as in my Letters Patent herein referred to, and a description of this mode of operation is, therefore, not necessary since it does not in any way affect the set indicator or the justifying indicator.

It is not my intention to limit the invention to the precise details of construction shown in the accompanying drawings, it being apparent that such may be varied without departing from the spirit and scope of the invention.

Having described the invention, what I claim as new and desire to have protected by Letters Patent is:

1. In a printing machine the combination with a printing couple, one of the members of which has a shaft, a plurality of type carrying members mounted thereon, a member for turning said shaft, a setting bar, and means for progressively disengaging said setting bar from said type carrying members, of a setting mechanism containing an indicating mechanism having thereon all printing characters carried by each of said type carrying members, and means having indicia thereon co-operating with said characters and actuated in accordance with the turning movement of said shaft.

2. In a printing machine the combination with a printing couple, one of the members of which has a shaft, a plurality of type carrying members mounted thereon and each carrying a justifying mechanism, a member for turning said shaft, a setting bar, and means for progressively disengaging said setting bar from said type carrying members and bringing it into engaging relation with the justifying mechanisms upon said members, of a setting mechanism containing a justifying indicator including consecutively numbered movable members corresponding in number with the number of said type carrying members, an index finger carried by and movable with the means operative upon said setting bar, means for imparting a step by step movement to said means operative upon said setting bar, a member movable with said index finger and adapted to actuate said movable members, and selectively operative means adapted to actuate said last named member by turning movement of said shaft.

3. In a printing machine the combination with a printing couple, one of the members of which has a shaft, a plurality of type carrying members mounted thereon and each carrying a justifying mechanism, a member for turning said shaft, a setting bar, and means for progressively disengaging said setting bar from said type carrying members and bringing it into engaging relation with the justifying mechanisms upon said members, of a setting mechanism containing a justifying indicator including consecutively numbered movable members corresponding in number with the number of said type carrying members, an index finger carried by and movable with the means operative upon said setting bar, means for imparting a step by step movement to said means operative upon said setting bar, a member movable with said index finger and adapted to actuate said movable members, and selectively operative means adapted to actuate said last named member by turning movement of said shaft, and an indicating mechanism having thereon all printing characters carried by each of said type carrying members, and means 75 having indicia thereon co-operating with said

characters and actuated in accordance with the turning movement of said shaft.

4. In a printing machine the combination with a printing couple, one of the members of which has a shaft, a plurality of type carrying members mounted thereon, a hand wheel for turning said shaft, a setting bar, and means for progressively disengaging said setting bar from said type carrying members, of a power actuated driving shaft, a driven shaft, a crank shaft, connections between said crank shaft and said setting bar for imparting a step by step movement thereto, a crank upon said driven shaft, connections between said crank and said crank shaft, an electrically actuated clutch mechanism between said driving and said driven shafts, a switch mechanism having a movable member adjacent said hand wheel for controlling the circuit to said clutch mechanism, and means for limiting the operative moment of said clutch mechanism to a single actuation of said setting bar.

5. In a printing machine the combination with a printing couple, one of the members of which has a shaft, a plurality of type carrying members mounted thereon, a member for turning said shaft, a setting bar, and means for progressively disengaging said setting bar from said type carrying members, of a setting mechanism containing an indicating mechanism including therein fixed means having thereon all printing characters carried by each of said type carrying members, and a tape movable in relation to said fixed means and having indicia thereon co-operating with said characters and actuated in accordance with the turning movement of said shaft.

6. In a printing machine the combination with a printing couple, one of the members of which has a shaft, a plurality of type carrying members mounted thereon, a member for turning said shaft, a setting bar, and means for progressively disengaging said setting bar from said type carrying members, of a setting mechanism containing an indicating mechanism, including two plates spaced apart, one of said plates having thereon printing characters corresponding with those throughout 180° of each type carrying member, and the other having printing characters corresponding with those throughout the other 180° of said members, and a tape positioned between and movable in relation to said plates and having indicia thereon co-operating with said characters and actuated in accordance with the turning movement of said shaft.

7. In a printing machine the combination with a printing couple, one of the members of which has a shaft, a plurality of type carrying members mounted thereon, a hand wheel for turning said shaft, a setting bar, and means for progressively disengaging said setting bar from said type carrying members, of a setting mechanism containing an indicating mechanism, two plates spaced apart, one of said plates having thereon printing characters corresponding with those throughout 180° of each type carrying member, and the other having printing characters corresponding with those throughout the other 180° of said members, a tape positioned between and movable in relation to said plates and having indicia thereon co-operating with said characters, said tape passing about and engaging said hand wheel, whereby it is actuated in accordance with the turning movement of said shaft, and an adjusting mechanism operative to take up slack in said tape.

8. In a printing machine the combination with a printing couple, one of the members of which

turning of said hand wheel for setting the justifying mechanism upon any type carrying member, means for automatically disengaging said slide from said hand wheel, and means simultaneously imparting a return movement to all gauge slides which have been moved during the setting of a line of type.

13. In a printing machine the combination with a printing couple, one of the members of which has a shaft, a plurality of type carrying members mounted thereon, a hand wheel for turning said shaft, a setting bar, and means for progressively disengaging said setting bar from said type carrying members, of a power actuated driving shaft, a driven shaft, a crank shaft, connections between said crank shaft and said setting bar for imparting a step by step movement thereto, a crank upon said driven shaft, connections between said crank and said crank shaft, a clutch mechanism between said driving and said driven shafts, a solenoid actuating said clutch mechanism, a controlling switch mechanism having a movable member adjacent said hand wheel, two relays having respectively a normally open and a normally closed switch mechanism in circuit with said solenoid and with said controlling switch mechanism, a solenoid actuated switch mechanism in circuit with said normally closed relay, whereby the energizing of one of said relays will energize said solenoid, and the energizing of the other relay will de-energize said solenoid, and switches actuated by said relays respectively, whereby so long as said controlling switch is closed, both said relays remain energized.

14. In a printing machine the combination with a printing couple, one of the members of which has a shaft, a plurality of type carrying members mounted thereon, a hand wheel for turning said shaft, a setting bar, and means for progressively disengaging said setting bar from said type carrying members, of a power actuated driving shaft, a driven shaft, a crank shaft, connections between said crank shaft and said setting bar for imparting a step by step movement thereto, a crank upon said driven shaft, connections between said crank and said crank shaft, a clutch mechanism between said driving and said driven shafts, a solenoid actuating said clutch mechanism, a controlling switch mechanism having a movable member adjacent said hand wheel, two relays having respectively a normally open and a normally closed switch mechanism in circuit with said solenoid and with said controlling switch mechanism, a solenoid actuated switch mechanism in circuit with said normally closed relay, whereby the energizing of one of said relays will energize said solenoid, and the energizing of the other relay will de-energize said solenoid, switches actuated by said relays respectively, whereby so long as said controlling switch is closed, both said relays remain energized, an arc suppressor in shunt with said relays, and a switch mechanism and a resistance connected in parallel in the line to said solenoid, whereby either alternating or direct current may be used.

15. In a printing machine the combination with a printing couple, one of the members of which has a shaft, a plurality of type carrying members mounted thereon and each carrying a justifying mechanism, a hand wheel for turning said shaft, a setting bar, and means for progressively disengaging said setting bar from said type carrying members and bringing it into engaging relation with the justifying mechanisms

upon said members, of a setting mechanism containing a justifying indicator including consecutively numbered movable members corresponding in number with the number of said type carrying members, an index finger carried by 5 and movable with the means operative upon said setting bar, means for imparting a step by step movement to said means operative upon said setting bar, a member movable with said index finger and adapted to actuate said movable members, and selectively operative means adapted to actuate said last named member by turning movement of said shaft, and an indicating mechanism including two plates spaced apart, one of said plates having thereon printing characters 15 corresponding with those throughout 180° of each type carrying member, and the other having printing characters corresponding with those throughout the other 180° of said members, and a tape passing about said hand wheel positioned 20 between and movable in relation to said plates and having indicia thereon cooperating with said characters.

16. In a printing machine the combination with a printing couple, one of the members of which has a shaft, a plurality of type carrying members mounted thereon and each carrying a justifying mechanism, a member for turning said shaft, a setting bar, and means including a sleeve upon said shaft for progressively disengaging 25 said setting bar from said type carrying members and bringing it into engaging relation with the justifying mechanisms upon said members, of a setting mechanism containing a justifying indicator including a base having a plurality of transverse grooves therein of a width and being spaced apart a distance each equaling one-half the thickness of a type carrying member and corresponding in number with the number of type carrying members, consecutively numbered 30 gauge slides in said grooves, a member movably mounted upon the sleeve upon said shaft having an index finger adjacent said base and said gauge slides, means carried thereby adapted to impart longitudinal movement to any gauge 35 slide, movable means extending along said base and operative upon said member, selectively operative means adapted to actuate said movable means and to be selectively connected with the member for turning said shaft, and means simultaneously imparting a return movement to all 40 gauge slides which have been moved during the setting of a line of type, an indicating mechanism having thereon all printing characters carried by each of said type carrying members, and 45 means having indicia thereon co-operating with said characters and actuated in accordance with the turning movement of said shaft.

17. In a printing machine the combination with a printing couple, one of the members of which has a shaft, a plurality of type carrying members mounted thereon and each carrying a justifying mechanism, a hand wheel for turning said shaft, a setting bar, and means including a sleeve upon said shaft for progressively disengaging 50 said setting bar from said type carrying members and bringing it into engaging relation with the justifying mechanisms upon said members, of a setting mechanism containing a justifying indicator including a base having a plurality of transverse grooves therein of a width and being spaced apart a distance each equaling one-half the thickness of a type carrying member and corresponding in number with the number of type carrying members, consecutively 55

numbered gauge slides in said grooves, a member 5
movably mounted upon the sleeve upon said
shaft having an index finger adjacent said base
and said gauge slides, means carried thereby
adapted to impart longitudinal movement to any
gauge slide, movable means extending along said
base and operative upon said member, selectively
operative means adapted to actuate said movable
means and to be selectively connected with
10 said hand wheel, and means simultaneously im-
parting a return movement to all gauge slides
which have been moved during the setting of a
line of type, an indicating mechanism including
two plates spaced apart, one of said plates hav-
15 ing thereon printing characters corresponding
with those throughout 180° of each type carry-
ing member, and the other having printing char-
acters corresponding with those throughout the
other 180° of said members, and a tape passing
20 about said hand wheel positioned between and
movable in relation to said plates and having in-
dicia thereon co-operating with said characters.

18. In a printing machine the combination with
a printing couple, one of the members of which
25 has a shaft, a plurality of type carrying mem-
bers mounted thereon and each carrying a justi-
fying mechanism, a hand wheel for turning said
shaft, a setting bar, and means for progressively
disengaging said setting bar from said type car-
30 rying members and bringing it into engaging re-
lation with the justifying mechanisms upon said
members, of a setting mechanism containing a
justifying indicator including consecutively num-
bered movable members corresponding in num-
35 ber with the number of said type carrying mem-
bers, an index finger carried by and movable
with the means operative upon said setting bar,
a power actuated driving shaft, a driven shaft,
a crank shaft, connections between said crank
40 shaft and said setting bar for imparting a step
by step movement thereto, a crank upon said
driven shaft, connections between said crank and
said crank shaft, a clutch mechanism between
said driving and said driven shafts, a solenoid
45 actuating said clutch mechanism, a controlling
switch mechanism having a movable member ad-
jacent said hand wheel, two relays having re-
spectively a normally open and a normally closed
switch mechanism in circuit with said solenoid
50 and with said controlling switch mechanism, a
solenoid actuated switch mechanism in circuit
with said normally closed relay, whereby the en-
ergizing of one of said relays will energize said
solenoid, and the energizing of the other relay
55 will de-energize said solenoid, and switches actu-
ated by said relays respectively, whereby so long
as said controlling switch is closed, both said
relays remain energized.

19. In a printing machine the combination with
a printing couple, one of the members of which
60 has a shaft, a plurality of type carrying mem-
bers mounted thereon and each carrying a justi-
fying mechanism, a hand wheel for turning said
shaft, a setting bar, and means for progressively
disengaging said setting bar from said type car-
65 rying members and bringing it into engaging re-
lation with the justifying mechanisms upon said
members, of a setting mechanism containing a
justifying indicator including consecutively num-
bered movable members corresponding in num-
70 ber with the number of said type carrying mem-
bers, an index finger carried by and movable with
the means operative upon said setting bar, means
for imparting a step by step movement to said
means operative upon said setting bar, a member
75

movable with said index finger and adapted to
actuate said movable members, and selectively
operative means adapted to actuate said last
named member by turning movement of said
shaft, an indicating mechanism including two 5
plates spaced apart, one of said plates having
thereon printing characters corresponding with
those throughout 180° of each type carrying mem-
ber, and the other having printing characters
corresponding with those throughout the other 10
180° of said members, and a tape passing about
said hand wheel positioned between and movable
in relation to said plates and having indicia
thereon cooperating with said characters, a power
actuated driving shaft, a driven shaft, a crank 15
shaft, connections between said crank shaft and
said means for moving said setting bar, a crank
upon said driven shaft, connections between said
crank and said crank shaft, a clutch mechanism
between said driving and said driven shafts, a 20
solenoid actuating said clutch mechanism, a con-
trolling switch mechanism having a movable
member adjacent said hand wheel, two relays
having respectively a normally open and a nor-
mally closed switch mechanism in circuit with 25
said solenoid and with said controlling switch
mechanism, a solenoid actuated switch mecha-
nism in circuit with said normally closed relay,
whereby the energizing of one of said relays will
energize said solenoid, and the energizing of the 30
other relay will de-energize said solenoid, and
switches actuated by said relays respectively,
whereby so long as said controlling switch is
closed, both said relays remain energized.

20. In a printing machine the combination 35
with a printing couple, one of the members of
which has a shaft, a plurality of type carrying
members mounted thereon and each carrying a
justifying mechanism, a member for turning
said shaft, a setting bar, and means including 40
a sleeve upon said shaft for progressively dis-
engaging said setting bar from said type car-
rying members and bringing it into engaging
relation with the justifying mechanisms upon
said members, of a setting mechanism con-
45 taining a justifying indicator including a base
having a plurality of transverse grooves therein
of a width and being spaced apart a distance
each equaling one-half the thickness of a type
carrying member and corresponding in number 50
with the number of type carrying members,
consecutively numbered gauge slides in said
grooves, a member movably mounted upon the
sleeve upon said shaft having an index finger
55 adjacent said base and said gauge slides, means
carried thereby adapted to impart longitudinal
movement to any gauge slide, movable means
extending along said base and operative upon
said member, selectively operative means adapt-
60 ed to actuate said movable means and to be
selectively connected with the member for turn-
ing said shaft, and means simultaneously im-
parting a return movement to all gauge slides
which have been moved during the setting of a
65 line of type, an indicating mechanism having
thereon all printing characters carried by each
of said type carrying members, means having
indicia thereon co-operating with said charac-
ters and actuated in accordance with the turn-
70 ing movement of said shaft, a power actuated
driving shaft, a driven shaft, a crank shaft, con-
nections between said crank shaft and said
sleeve, a crank upon said driven shaft, con-
nections between said crank and said crank
75 shaft, a clutch mechanism between said driving

- and said driven shafts, a solenoid actuating said clutch mechanism, a controlling switch mechanism having a movable member adjacent the member for turning said shaft, two relays having respectively a normally open and a normally closed switch mechanism in circuit with said solenoid and with said controlling switch mechanism, a solenoid actuated switch mechanism in circuit with said normally closed relay, whereby the energizing of one of said relays will energize said solenoid, and the energizing of the other relay will de-energize said solenoid, and switches actuated by said relays respectively, whereby so long as said controlling switch is closed, both said relays remain energized.
21. In a printing machine the combination with a printing couple, one of the members of which has a shaft, a plurality of type carrying members mounted thereon and each carrying a justifying mechanism, a hand wheel for turning said shaft, a setting bar, and means including a sleeve upon said shaft for progressively disengaging said setting bar from said type carrying members and bringing it into engaging relation with the justifying mechanisms upon said members, of a setting mechanism containing a justifying indicator including a base having a plurality of transverse grooves therein of a width and being spaced apart a distance each equalling one-half the thickness of a type carrying member and corresponding in number with the number of type carrying members, consecutively numbered gauge slides in said grooves, a member movably mounted upon the sleeve upon said shaft having an index finger adjacent said base and said gauge slides, means carried thereby adapted to impart longitudinal movement to any gauge slide, movable means

extending along said base and operative upon said member, selectively operative means adapted to actuate said movable means and to be selectively connected with said hand wheel, and means simultaneously imparting a return movement to all gauge slides which have been moved during the setting of a line of type, an indicating mechanism including two plates spaced apart, one of said plates having thereon printing characters corresponding with those throughout 180° of each type carrying member, and the other having printing characters corresponding with those throughout the other 180° of said members, and a tape passing about said hand wheel positioned between and movable in relation to said plates and having indicia thereon co-operating with said characters, a power actuated driving shaft, a driven shaft, a crank shaft, connections between said crank shaft and said sleeve, a crank upon said driven shaft, connections between said crank and said crank shaft, a clutch mechanism between said driving and said driven shafts, a solenoid actuating said clutch mechanism, a controlling switch mechanism having a movable member adjacent said hand wheel, two relays having respectively a normally open and a normally closed switch mechanism in circuit with said solenoid and with said controlling switch mechanism, a solenoid actuated switch mechanism in circuit with said normally closed relay, whereby the energizing of one of said relays will energize said solenoid, and the energizing of the other relay will de-energize said solenoid, and switches actuated by said relays respectively, whereby so long as said controlling switch is closed, both said relays remain energized.

BLACKWELL K. MURCHISON.
